13 Inventor:
W.S. Beebe

UNITED STATES PATENT OFFICE.

DANIEL S. BEEBE, OF CHICAGO, ILLINOIS, ASSIGNOR TO THE VITROLITE COMPANY, OF PARKERSBURG, WEST VIRGINIA, A CORPORATION OF WEST VIRGINIA.

ANCHOR BETWEEN VITREOUS SLABS ARRANGED AT AN ANGLE TO EACH OTHER.

Application filed May 25, 1925. Serial No. 32,610.

To all whom it may concern:

Be it known that I, DANIEL S. BEEBE, a citizen of the United States, residing at Chicago, county of Cook, State of Illinois, have 5 invented a certain new and useful Improvement in Anchors Between Vitreous Slabs Arranged at an Angle to Each Other, and declare the following to be a full, clear, and exact description of the same, such as will 10 enable others skilled in the art to which it pertains to make and use the same, reference being had to the accompanying drawings, which form a part of this specification.

The object of the present invention is to 15 produce a simple and novel means for effectively fastening together two slabs of vitreous material or the like positioned in contact with each other and at an angle to each other.

20 The various features of novelty whereby my invention is characterized will herein-after be pointed out with particularity in the claims; but, for a full understanding of my invention and of its objects and advan- 25 tages, reference may be had to the following detailed description taken in connection with the accompanying drawings, wherein:

Figure 1 is a front view of the endmost booth or compartment of a row made out of 30 slabs of vitreous material; Fig. 2 is a section taken approximately on line 2—2 of Fig. 1; Fig. 3 is a perspective view of a part of the left hand side slab in Fig. 1; Fig. 4 is a view similar to Fig. 3, showing the right hand side slab in Fig. 1; Fig. 5 is a perspective view of one of the corner pieces or angles; Fig. 6 is a section on a large scale through the left hand corner of the booth taken approximately on line 6—6 of Fig. 1; 40 Fig. 7 is a view similar to Fig. 6, taken approximately on line 7—7 of Fig. 1 and Fig. 8 is a section taken approximately on line 8—8 of Fig. 6; and Fig. 9 is an edge view of the front end of the anchoring strap and auxiliary straps shown in Fig. 7, separated 45 from each other.

Referring to the drawings, 1 and 2 represent partitions or walls of vitreous material, extending from a wall 3 of a building or 50 room, which wall forms the rear side or wall of a plurality of booths. To the front edge of the member 1 is fixed a front panel 4 lying at right angles to said member and having its outer edge flush with the outer face

of the latter. Extending across the front 55 edge of the wall or partition 2, at right angles to the latter, and projecting in both directions therefrom is a front panel 5. The members 4 and 5 are spaced apart to form a door opening between them, although 60 the present invention is not limited to this particular design.

Each of the side walls or partitions is made of two slabs laid against each other and secured together by suitable cement; 65 the cement being indicated at 6 in Figs. 6, 7, and 8. Within the space between the two members of each slab are placed long flat metal strips 7 that project beyond the front edges of the slabs. In the arrangement shown, there are two of these strips, one near the top, and one near the bottom of each slab. The projecting end of each strip is bent laterally, as indicated at 8, so as to lie flat against the corresponding 70 front panel; one or both of the members of each slab being notched in the front edge so that the lateral arm of each bend will lie within the plane of the front edge of the slab. Only the inner member of the slab 80 1 is notched, the notches being indicated at 9, 9. The notches in the slab 2, indicated at 10, 10 extend through the thickness of the entire slab, that is through both members 85 of the slab.

The manner of securing the outer slab 1 to the front member 4 is best shown in Fig. 6. The notches in this slab are on the inner of the two members, so that the ends 8 of the straps project inwardly from this slab along 90 the member 4. In the corner between the members 1 and 4 are placed two angle brackets 11 each hollowed out on the outer sides to form pockets 12, one of which is adapted to receive one of the strap ends 8. 95 Only one pocket is required in each bracket, but the two flanges of the bracket may be made alike, for the sake of symmetry in the distribution of metal and to make them reversible. The flange of the bracket overlying one of the strap ends 8, and said strap end have registering holes through which extends a suitable fastening element that clamps the bracket to the member 4. In the arrangement shown, there is a stud 13 fixed 100 to the panel 4 and passing through the registering holes in the strap end 8 and the overlying bracket flange; the stud having a nut 105

14 on the outer end. It will thus be seen that only a single fastening device is required at each strap end.

Where the front panel projects laterally in both directions from the wall or partition, as does the panel 5 with respect to the slab 2, a construction such as illustrated in Fig. 7 is employed. The strap end 8 projects laterally from one side of the slab, as in the construction previously described. Laid flat against the front or outer face of the part 8 is a strap section 15 about twice as long as said strap end, one-half of the member 15 projecting from the side of the member 7 opposite to that on which the end 8 lies. In order to build up the thickness of what may be termed the head on the member 7 on what may be termed the free end of the strap section 15, I may lay a short strap section 16 on the inner side of the member 15. In assembling the structure, the strap 15 is laid against the panel 5 with the strap end 8 overlying one-half thereof, and the short strap section 16 is placed behind the other half. The elements 15 and 8, and the elements 15 and 16, have registering holes 17 and 18 through which fastening means such as heretofore described may pass; there being one of the brackets 11 in each of the two corners between the slab 2 and the panel 5. It will be seen that it is immaterial whether the strap members 8, 15 and 16 are secured together or not before being assembled in the booth construction, because they will all be tied together by the means that fasten them and the brackets to the panel 5.

It will thus be seen that I have produced a simple and novel construction that may be completely built in the factory and which may be set up quickly and securely at the place of use by comparatively unskilled labor and without danger that the assembling will be improperly done; since all that the assembler has to do is to place the parts in their proper relative positions and then screw on a few nuts.

While I have illustrated and described with particularity only a single preferred form of my invention, I do not desire to be limited to the exact structural details thus illustrated and described; but intend to cover all forms and arrangements which come within the definitions of my invention constituting the appended claims.

55 I claim:

1. In combination, a wall lying at right angles to and engaged with a second wall, the first wall having an element extending along the second wall from the juncture, a member fitted into the corner between said walls and overlying said element, and fastening means extending through said member and said element and into said second wall.

60 2. In combination, a wall made of two

parts secured together face to face, a strap lying and secured between the parts of and projecting from an edge of the said wall, a second wall lying against the edge and extending transversely of the first wall, the 70 projecting end of said strap being bent laterally to lie against the exposed portion of the face of said second wall and being secured thereto.

3. In combination, a wall made of two 75 parts secured together face to face, a strap lying and secured between the parts of said wall and having an end projecting therefrom and bent laterally with respect thereto, a second wall lying against said edge and engaged with the projecting end of said strap, a member fitted into the angle between said walls and overlying said strap end, and fastening means for said member serving to anchor said strap end to said 80 second wall.

4. In combination, a wall made of two parts secured together face to face, a strap lying and secured between the parts of said wall and projecting from an edge thereof, the projecting end of the strap being bent laterally, a second wall lying against said edge and engaged with said projecting end of the strap, a bracket fitted into the angle between said walls and overlying said strap end, and a fastening means passing through said bracket and strap and into the second 90 wall.

5. In combination, a wall made of two parts secured together face to face, a strap lying and secured between the parts of the wall and projecting from an edge of the latter, the projecting end of the strap being bent laterally, a second wall lying against said edge and engaged with the projecting end of said strap, a bracket fitted into the angle between said walls and overlying said strap end, said bracket having elements engaging both walls at a distance from the corner, and means for securing said bracket in place and simultaneously anchoring said strap end to said second wall.

6. In combination, a wall made of two parts secured together face to face, a strap lying and secured between said parts of the wall and projecting from an edge of the latter, the projecting end of said strap being bent laterally, a second wall lying against said edge and engaged with said strap end, a bracket fitted into the angle between said walls and overlying said strap end, said bracket having faces engaged with both walls, and a single fastening device for said bracket passing through the latter and through said strap end and into said second wall.

7. In combination, two walls lying at right angles to and in contact with each other, one of said walls having an element fixed thereto and projecting laterally from 130

one edge along the face of the second wall, a bracket fitted into the angle between said walls and having on the side facing said second wall a pocket to receive said element and conceal it, and a fastening device extending from said bracket into said second wall.

8. In combination, two walls extending transversely of each other with an edge of
10 the first wall engaged with the face of the second wall, a strap fixed into the first wall and extending laterally from said edge along the other wall, a second strap lying against the other strap and extending past
15 the said edge to the opposite side of the first wall in contact with the second wall, brackets fitted into the angles between said walls and overlying said straps, and fastening means extending from said brackets
20 through said straps and into said second wall.

9. In combination, two walls arranged

transversely of each other with an edge of one wall in contact with a face of the second wall, brackets fitted into the angles between said walls, anchoring means extending from said edge in opposite directions between said brackets and the said second wall, and fastening elements extending from each bracket through said anchoring means and
25 into said second wall.

10. In combination, two walls arranged transversely of each other with an edge of one wall in contact with a face of the second wall, brackets fitted into the angles between said walls, anchoring means extending from said edge in opposite directions between said brackets and the said second wall, and means for fastening said brackets,
30 and at the same time the said anchoring means, to said second wall.

In testimony whereof, I sign this specification.

DANIEL S. BEEBE.
